(Model.)

H. S. GRACE.

HAND PIECE FOR DENTAL ENGINES.

No. 380,433.

Patented Apr. 3, 1888.

UNITED STATES PATENT OFFICE.

HENRY S. GRACE, OF SAN FRANCISCO, CALIFORNIA, ASSIGNOR OF ONE-HALF
TO CHARLES W. DECKER, OF SAME PLACE.

HAND-PIECE FOR DENTAL ENGINES.

SPECIFICATION forming part of Letters Patent No. 380,433, dated April 3, 1888.

Application filed May 28, 1887. Serial No. 239,712. (Model.)

To all whom it may concern:

Be it known that I, HENRY S. GRACE, of the city and county of San Francisco, State of California, have invented an Improvement in 5 Hand-Pieces for Dental-Engines; and I hereby declare the following to be a full, clear, and exact description of the same.

My invention relates to a dental implement; and it consists in the constructions and combinations of devices, which I shall hereinafter fully describe and claim.

Figure 1 is a longitudinal section of the apparatus. Fig. 2 is an outside view of the same. Fig. 3 shows the point directly connected with the flexible driving-cable so that it may be used as a drill or burring-tool. Fig. 15 Fig. 4 shows the point adapted to be used as a plunger. Fig. 5 shows a mechanism for reversing the direction of the plugging movement and 20 changing its angle. Fig. 6 is an enlarged view of the interior shell and the connecting device intermediate between the parts.

A is the outer cylindrical shell of the hand-piece, having the top B at the upper end 25 through which the cable or flexible driving-shaft C enters to actuate the internal mechanism.

F' is the spindle, into the point of which is 30 inserted a split shank or socket which forms a chuck into which the ends of any and all tools which are to be used with the apparatus may be inserted. This chuck may be interchangeable. The inner end of this chuck screws into an interior shank, F, and this latter is operated by a milled head, G, at its upper end, by turning which it is drawn up and with it the chuck or socket E, so that as it is drawn into the conical point of the spindle F' it is compressed upon the tool so as to hold it 35 firmly, whatever may be its shape or size. This makes it possible to use a great many kinds of tools in a single hand-piece without having the ends especially fitted to any particular holding device.

H is a slide which fits outside the cylindrical body A, and moves up or down, so as to expose or cover openings in the side of the body which are just opposite the milled head G, thus allowing the operator easy access to the

milled head when it is desired to turn it. In 50 order to connect this lower tool-holding portion of the device with the upper and actuating portion, I employ an intermediate piece, I, which is formed, as shown in Fig. 6, with the longitudinal projecting bars all around it, 55 and the ends of these bars fit into corresponding depressions or sockets on the parts J and U', as plainly shown in Fig. 6.

The piece I has one end, L, made to act as a hammer when the tool is to be used as a 60 plunger, in which case it is reversed so that the end L is toward the point where the tool is secured, and it then rests upon the end of that portion carrying the tool itself, as is more fully shown in Fig. 4.

In order to soften the blow which is given by the plunger, I have introduced between the tool and the mallet or hammer portion leather, wood, or similar substance, as shown at M, which serves as a sort of cushion to relieve the disagreeable effects of a blow, making it much pleasanter than when metal strikes against metal. The buffer may be upon one or both the meeting ends, or simply placed between them.

The part J (shown in Fig. 6, and also in Figs. 1 and 3,) is in the form of a yoke having in the head at the lower end of the yoke a square hole at N, which fits over the square shank on the spindle F, so that when the 80 flexible driving-cable is connected directly with this portion, as shown in Fig. 3, it will cause the tool to rotate when it is used as a drill.

All that upper portion or middle body of 85 the hand-piece between the cap B and the tool-holding portion and cone D may be omitted and the cable connected directly with this lower portion, the device then being used simply as a drill alone. In Fig. 4 I have shown 90 a similar construction in which the cable is connected with that portion serving as a plunger or mallet, the body or intermediate portion being omitted in this case as well.

In Fig. 1 the cable or flexible driving-shaft C 95 passes in through the head and connects with a shaft carrying a portion O of the clutch, which slides upon a feather, so that it may be raised

or depressed by means of a pin which enters a groove in the clutch-ring, and this pin is connected with a sleeve, P, sliding in an angular or Z-shaped slot upon the outside of the exterior case, and passes through the cap B, so that by raising the sleeve up the clutch is thrown out of engagement with the part Q, and by moving it down it is thrown into engagement, so as to drive this part.

10 R is the cam by which the hammer or mallet is raised as the shaft rotates, and S is the spring by which it is forced down to give the blow when the pin passes over the highest point of the cam.

15 The part K, referred to and shown in Fig. 6, forms an interior sleeve within the outer casting, within which the spring S and the shaft carrying the operating cam are connected, as shown in Fig. 1. A pin, T, passes through 20 the side of this interior cylindrical sleeve and extends inwardly above the inclines of the cam, so that as the cam-shaft rotates these inclines will successively raise the pin, carrying with it the sleeve K and the parts below which 25 are connected therewith.

In order to connect the intermediate sleeve with the part K, I have formed a groove or channel, U, around the lower end of the extension-piece U', which rotates in this part K, 30 as is more plainly shown in Fig. 1, and there are corresponding grooves or channels inside the longitudinal bars I, so that a ring lying in these channels will unite them like a key and hold the parts together. The part U' is driven 35 by the lower end of the cam-shaft, which is made square and fits into a corresponding socket in U'.

When the device is to be used as a drill or burring-instrument, the part I is reversed, the 40 hammer portion L then extending toward and into the lower end of the part K of the extension thereon, and the opposite end simply engages with the projections and sockets of the part J, thus making the device easily interchangeable.

In order to allow the interior cylindrical sleeve K, which actuates the mallet, to move up and down within the outer casing when 45 acted upon by the cams R, and at the same time prevent its being turned around within the outer case, I have formed it with a channel or depression at one side, as shown at V, Fig. 6, and into this depression a screw or pin, W, (shown at Fig. 1,) enters and acts as a 55 guide, thus allowing the sleeve K to move up and down without turning.

The movement of the chuck and the sweep of the blow are regulated by means of the screw d and a lock-nut for holding it in place. The 60 yoke J is held on the square shoulder of the spindle F' by a nut, e, and lost motion in the spindle is taken up by a nut, f, being screwed down upon the shoulder of the spindle, said nut having threads engaging the inner surface 65 of the cone D, as shown in Fig. 1.

In some cases it is desirable to use the mal-

let or plunger in positions where it cannot be operated to advantage in a direct line, and this is effected by means of an extension at right angles with the point D, as shown in Fig. 5, 70 with a lever, a, fulcrumed within it, having one end connected with the reciprocating piece, which is held by the chuck or tool-holder, and the other end is connected with the plugging-tool b, which extends upward or 75 returns parallel with the shank of the implement, so that through the lever a the blow is given in an opposite direction to the impulse of the mallet.

In order to enable me to change the angle of 80 this tool and use it in different directions, I have hinged the outer portion, X', of the angular extension from the point and fitted it to the part X, so that it may turn about this part and about the pivot of the lever and tool, 85 so that the tool itself, standing between guides upon the hinged portion X, will partake of the motion of this portion and will be caused to point at an angle having any desired degree of inclination with the actuating-lever a. 90

Having thus described my invention, what I claim as new, and desire to secure by Letters Patent, is—

1. In a dental hand-piece, the exterior casing, the interior cylinder, within which are 95 fitted the rotary cam-shaft and the spiral spring which actuates the mallet, in combination with the spindle having the tool-holder and adjusting mechanism, and the intermediate reversible connecting-piece I, by which 100 the two are united, substantially as described.

2. In a dental hand-piece, the exterior case, the interior cylinder having the slot and guiding-pin upon one side and the cam-shaft and spring fitted to its interior, in combination 105 with the clutch, one portion of which is secured to the end of the cam-shaft, and the other slides upon a feather in the driving-shaft, which enters the upper end of the hand-piece, together with the sliding ring and pin, 110 whereby the clutch may be made to engage or disengage with the cam-shaft, substantially as herein described.

3. In combination with the spindle, the tool-holder, and the connecting devices, as 115 shown, the yoke J, within which the milled head of the chuck-operating screw is fitted to turn, said device having a square opening in the lower end or cross-bar, whereby it is connected with the spindle, so as to rotate the 120 same by the action of the flexible driving-shaft which connects with this device, substantially as described.

4. The dental plunger having an extension at right angles with a tip, within which a 125 lever is journaled, so as to actuate a plugging-instrument, in combination with a supplemental hinged or jointed tip, X', carrying a guide for the plugging-tool, said extension and tool being adjustable to any angle of inclination 130 with the actuating-lever, substantially as described.

5. The rotary spindle, tool-holding chuck, and the driving mechanism of a dental plug-
ger, in combination with the adjusting nut or
sleeve *f*, engaging a shoulder on said spindle,
and externally threaded, whereby the spindle
may be made to run light and lost motion be
taken up, substantially as herein described.

In witness whereof I have hereunto set my
hand.

HENRY S. GRACE.
